UNITED STATES PATENT OFFICE.

ISAAC N. ARMENT AND ALLEN E. SCOTT, OF DAYTON, WASHINGTON TERRITORY.

TOOTH-BRUSH AND CASE.

SPECIFICATION forming part of Letters Patent No. 246,934, dated September 13, 1881.

Application filed June 28, 1881. (Model.)

To all whom it may concern:

Be it known that we, ISAAC N. ARMENT and ALLEN E. SCOTT, citizens of the United States, residing at Dayton, in the county of Columbia, 5 Washington Territory, have invented certain new and useful Improvements in Tooth-Brushes and Cases; and we do hereby declare the following to be a full, clear, and exact description of the invention, such as will enable 10 others skilled in the art to which it appertains to make and use the same, reference being had to the accompanying drawings, and to letters or figures of reference marked thereon, which form a part of this specification.

15 This invention has for its object to furnish an improvement in tooth-brushes and casings.

It consists in the construction and arrangement of the several parts hereinafter more particularly described, and pointed out in the 20 claim.

In the drawings, Figure 1 is a side elevation of the casing and brush. Fig. 2 is a longitudinal section of the same. Fig. 3 shows the casing with brush inserted therein, and Fig. 4 is 25 a detail of the casing.

a is a casing of suitable length, and adapted to receive and hold the brush. It is open at both ends, and is divided by a cross-partition, a', placed nearer one end than the other, into 30 the longer chamber a² and the shorter chamber a³. The shorter chamber is designed to hold the dentifrice, and its outer end is closed by the hinged cap a⁴. Near the outer and open end of the longer chamber there is provided 35 an inwardly-projecting flange or lip, a⁵, and is provided at the outer end with a spring- catch, a⁶.

b is the brush, of ordinary form. Its shank b' is provided with an enlarged end or head, b², adapted to fit snugly down into the open 40 end of the chamber a² and against the flange a⁵. The head b² is so formed that when its outer end is seated on the flange a⁵ the other end will be flush with the outer end of the casing and be held by the lip on the spring a⁶, 45 as shown in Fig. 2. The brush b and its shank can be removed from the position shown in Fig. 2, and reversed and the brush inserted into the casing. The inner end of the head b² will now be seated on the flange a⁵, and the lip 50 of the spring a⁶ will catch over the edge of the outer end of the said head, as shown in Fig. 3.

By the construction shown a very convenient pocket tooth-brush is provided. A small button, b³, or other suitable device is provided 55 on the outer end of the head b², by which the brush may be easily drawn out of the casing.

Having thus described our invention, what we claim, and desire to secure by Letters Patent, is—

The combination, with the casing a, having the inner projecting flange, a⁵, and the spring- catch a⁶, of the brush b, provided with a head, b², on the end of its shank fitted snugly into the open end of chamber a² and reversible, 65 substantially as set forth.

In testimony whereof we affix our signatures, in presence of two witnesses, on this 13th day of June, 1881.

ISAAC N. ARMENT.
ALLEN E. SCOTT.
